UNITED STATES PATENT OFFICE.

GENEVA FAYE WENTZ, OF ASHLAND, OHIO, ASSIGNOR TO THE FAULTLESS RUBBER COMPANY, OF ASHLAND, OHIO, A CORPORATION OF OHIO.

DESIGN FOR A BATHING-CAP.

47,176.

Specification for Design.

Patented Mar. 30, 1915.

Application filed December 21, 1914. Serial No. 878,452. Term of patent 7 years.

To all whom it may concern:

Be it known that I, GENEVA FAYE WENTZ, a citizen of the United States, residing at Ashland, in the county of Ashland and State of Ohio, have invented a new, original, and ornamental Design for Bathing-Caps, of which the following is a specification, reference being had to the accompanying drawing, forming part thereof.

The figure is a perspective view of my improved bathing cap, showing the same in shape for use in one way.

I claim:

The ornamental design for a bathing cap, as shown.

GENEVA FAYE WENTZ.
